FITTING FOR A BATHTUB

Robert J. Keller III, Richmond, Va., assignor to Kel-Win
Manufacturing Company, Inc., Chester, Va.

Filed Aug. 20, 1974, Ser. No. 499,048

Term of patent 14 years

Int. Cl. 23—07

U.S. Cl. D23—32

FIG. 1

FIG.2

FIG.3

FIG.4

FIG.5

FIG. 1 is a perspective view of a fitting for a bathtub showing my design;

FIG. 2 is a front elevational view thereof;

FIG. 3 is a top plan view thereof;

FIG. 4 is a side elevational view thereof; and

FIG. 5 is a bottom view thereof.

I claim:

The ornamental design of a fitting for a bathtub, substantially as shown.
